CALENDAR

Ray L. Neal, Drexel Hill, Pa., assignor to A. Pomerantz & Company, Philadelphia, Pa., a corporation of Pennsylvania

Application June 2, 1948, Serial No. 30,620

8 Claims. (Cl. 40—119)

1

The present invention relates to calendars or the like and it relates more particularly to diary-calendars of the type which indicate the date and also provide space for memoranda, etc.

An object of the present invention is to provide a new and improved construction for a calendar or the like. Another object of the present invention is to provide an inexpensive and efficient diary-calendar which is simple to use. Still another object of the present invention is to provide a diary-calendar constructed and arranged for greater legibility while, at the same time, providing adequate diary space for the notation of memoranda or the like.

Other objects and advantages of the present invention are apparent from the following detailed description, appended claims and accompanying drawings.

It has been suggested in the past to provide calendars which show, simultaneously, the current month as well as the past month and the coming month. It has also been suggested in the past to provide a calendar wherein the dates of the month are printed in squares sufficiently large to permit notation of memoranda to form a diary or record of past and future engagements or the like.

The present invention comprehends an improved wall-mounted diary-calendar construction which has not, to my knowledge, been heretofore used or suggested and which provides greater legibility and diary-space for the present month, as well as simultaneously visible large-size and legible calendars covering the preceding month and the coming month, and which is constructed and arranged to permit quick and easy change from one month to the next with means for retaining "used" month-pages in firmly-secured out-of-the-way position while permitting reference thereto without the need for removing the diary-calendar from its wall-mounting.

Generally speaking, the present invention contemplates a diary-calendar or engagement-calendar which can be sold in closed form generally resembling a book having front and back covers of cardboard or the like mounted on a hinge-member and which can be mounted on a wall with the free edge of the front cover member uppermost and with an integrally-formed depending flange or flap portion at said upper edge within which are mounted one or more concealed spring clamps tending to maintain the flange or flap in closed position so as to provide a resilient frictional engaging surface into

2

which the edges of individual calendar-pages can be tucked (after the months have passed) to maintain them in firmly-secured out-of-the-way position while permitting them to be folded back for reference if necessary. The individual month-sheets which are hingeably-connected intermediate the front and back covers are arranged so that the calendar for the current month appears as the lower page (the weeks of the month being arranged in horizontal lines, in conventional manner) with the individual days imprinted within squares or the like providing space for memoranda, and so that the preceding and following months appear in smaller size on the simultaneously visible upper page.

For the purpose of illustrating the invention, there are shown in the accompanying drawings forms thereof which are at present preferred, although it is to be understood that the various instrumentalities of which the invention consists can be variously arranged and organized and that the invention is not limited to the precise arrangements and organizations of the instrumentalities as herein shown and described.

Referring to the accompanying drawings in which like reference characters indicate like parts throughout:

Figure 1 represents a perspective view of one embodiment of the present invention shown in closed position, as it would be sold or stored.

Figure 2 represents an elevational view, showing the appearance of the calendar when opened to the first month.

Figure 3 represents a perspective view, on a somewhat reduced scale, showing the appearance of the calendar when hung on the wall and when turned to the next month.

Figure 4 represents a cross-sectional view generally along the line 4—4 of Figure 3.

Figure 5 represents a perspective view, on an enlarged scale, of one of the spring-clamps using the embodiment of Figures 1—4.

Figure 6 represents an elevational view of the front or top cover in unfolded position.

Figure 7 represents an elevational view of the rear or bottom cover in unfolded position.

In one embodiment of the present invention shown generally in Figures 1—3, I may provide a wall-calendar comprising a front or top cover 20, a rear or bottom cover 21 and a plurality of intervening pages pivotally mounted upon a hinge-member 22.

The top cover 20 is of generally two-ply construction formed from a generally rectangular

piece of cardboard, as indicated in Figure 6, by first bending along a central transverse fold line 23 and thereafter bending along fold lines 24 and 25, extending generally parallel to, and equidistant on either side of, the central fold line 23; aligned pairs of openings 26 and 27 being first formed along the fold lines 24 and 25 to receive a cord 28 by which the calendar can be hung from a nail or the like; the cord being knotted intermediate the openings 27 along the fold line 25 and extending through the openings 26 and 27 to form a loop on the other side of the fold line 24.

As can be seen particularly in Figures 3 and 4, the panels 29 and 30 extending intermediate the fold lines 24-23 and 25-23 form a two-ply depending flange at the top of the top cover 20 separated from the inner and outer plies of the cover 20 by the juxtaposed fold lines 24 and 25.

As indicated particularly in Figures 6, the free edges of the plies 31 and 32 are perforated as at 33 and 34 to provide a pivotal connection with the elongated hinge-member 22.

A pair of spring-clamps 35 are mounted so as to straddle the fold line 25 and thereby to press the panel 30 against the upper edge of the inner ply 31. The spring-clamps may be made of thin flat ribbon steel or the like having legs extending substantially the entire transverse dimension of the panel 30. If desired, a pair of integrally-formed pointed upwardly-projecting locking-ears 36 may be struck out from adjacent the ends of each spring-clamp so as to protrude inwardly and partially to pierce the panel 30 and the upper portion of the inner ply 31 so as to prevent dislodgement of the spring-clamps.

However, the locking-ears 36 may be omitted, especially since, as shown particularly in Figures 3 and 4, the fold line 24 overlies the closed ends of the spring-clamps 35 so that the panel 29 and the outer ply 32 tend to prevent dislodgement of the clamps.

The function of the clamps in the calendar construction of the present invention will be more fully described hereinbelow.

The rear or bottom cover 21 is also of two-ply construction including an inner-ply 37 and being provided with aligned perforations 40 and 41 to permit mounting on the hinge-member 22.

Also mounted on the hinge-member 22 intermediate the top and bottom covers 20 and 21 are twelve cardboard sheets representing the months of the year.

As shown in Figure 2, the first page or side of the first sheet may have the days of January arranged so that each week runs horizontally in the usual manner.

I prefer to arrange the individual days so that sufficient space is provided adjacent each date-number to permit the making of memoranda, etc. to permit the calendar to be used as a diary or record of engagements or the like. This can be done by providing horizontal and vertical ruling-lines 42 and 43 so that each day has a square for the making of memoranda, with the date-member in one of the upper corners of the square. However, the ruling-lines 42 and 43 may be omitted, if desired.

Upon the inner-ply 31 of the top cover 20 there are imprinted calendar-representations of the preceding and following months, 44 and 45 respectively; that is, the month of December of the preceding year and the following February. These supplemental calendar-representations 44 and 45 are, of course, appreciably smaller in size

than the main calendar representation 46 for the month of January and are intended simply to provide ready reference in calculating periods extending beyond the current month.

5 I also prefer to imprint the month and year designation for the main calendar-representation 46 along the lower edge of the inner-ply 31, as at 47 (instead of at the top of the calendar-page itself) so as to provide more room on the 10 calendar-page for the notation of memoranda, as mentioned above.

After the month of January has passed, the first calendar-page is adapted to be lifted up (pivoting on the hinge-member 22) so that its 15 free edge (which in the upwardly-lifted position terminates about half-way intermediate the upper and lower edges of the downwardly-depending flange portion of the top cover 20) can be tucked underneath the flange portion intermediate the panel 30 and the upper edge of the inner-ply 31. As can be seen particularly in Figure 4, the upper edge is thus frictionally retained in tucked-in position by the spring-clamps 35.

25 As can be seen particularly in Figure 3, the reverse side of the first calendar-sheet, which is now visible above the hinge-member 22, contains supplemental calendar-representations 48 and 49 for the previous and coming months, namely the 30 months of January and March. The lower edge of this reverse side also contains the current-month-and-year designation 50, namely "February 1948." The front side of the next calendar-sheet, which is now visible below the hinge-member 22, contains the main calendar-representation 51 for the month of February which is similar to the main calendar-representation 46, except, of course, for the variations in the days of the month.

40 From the foregoing it is apparent that, as each month passes, another calendar-sheet is flipped up and tucked underneath the flap-portion and is held in place by the spring-clamps 35, exposing successive current calendar-representations and 45 supplemental calendar-representations.

As indicated in Figure 7, the inner-ply 37 of the bottom cover 21 may be imprinted with a calendar showing all twelve months of the year.

The reverse side of the last calendar-sheet may 50 be provided with smaller-size yearly calendars (not shown) for the preceding and coming years so that, when the last calendar-sheet is lifted up, complete calendars covering a three-year period are visible simultaneously. This last feature is important in that it permits brief notations of appointments, dates, etc., far in advance.

As indicated in Figure 1, the novel calendar construction of the present invention can be sold 60 or transported or stored in compact closed book form, which can be quickly and easily opened and mounted on a wall and, thereafter, changed from month-to-month without taking the calendar down and without tearing off or otherwise 65 destroying the month-sheets.

Thus, the novel calendar construction affords a permanent record of memoranda, engagements, etc. which can be easily referred to by simply pulling out the upper edges of the turned-up pages 70 temporarily (and thereafter re-inserting them).

The closed book form of the calendar takes up little space so that a large number of them can be conveniently stored away to enable records to be kept over a long number of years.

75 The simplified one-piece construction for the

top cover and for the bottom cover makes the calendar inexpensive and easy to construct and assemble so that it can be sold at relatively low cost.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

Having thus described my invention, I claim as new and desire to protect by Letters Patent:

1. A calendar comprising a pair of covers including a top-cover and another cover both formed of generally form-retaining cardboard-like material, hole-engaging loop type hinge-members intervening the two covers, said hinge-members being spaced apart from each other along the adjoining marginal zones of said covers and a plurality of monthly-calendar panels of relatively form-retaining cardboard-like material all pivotally mounted upon said hinge-members, each panel having hinge-loop-receiving holes along one of its edges and being loosely and hingedly threaded onto said loop type hinge-members between said covers, whereby the calendar can be closed book-wise and opened and hung on a wall or the like for display in generally vertical position with the top-cover extending upwardly from said hinge-members, said monthly-calendar panels being substantially smaller than the top cover in the direction at a right angle to the hinge-line, said top-cover having an uppermost fold-line and an integrally-formed in-turned flap-portion extending inwardly from said fold-line and back upon the inner surface of said top-cover a distance substantially greater than the difference in the aforesaid dimensions of said top-cover and of said monthly-calendar panels, but a distance less than a third of the dimension of said top-cover from hinge-line to outer edge thereof, said flap-portion being secured to said top-cover near the fold-line between said cover and said flap-portion to resist the unfolding of said flap-portion in relation to said top-cover and to keep said flap-portion against the inner surface of said cover, but with the innermost edge-zone of said flap-portion being unattached to said cover so that the marginal zones of said monthly-calendar panels may be tucked beneath said flap-portion when said panels are turned into their positions against said top-cover, and resilient tensioning means operatively connected to said flap-portion and to the portion of said top-cover adjacent to said fold-line tending to hold said flap-portion to closed position, and means at the edge-zone of said top-cover at which said flap-portion is located for suspending said calendar on a wall or the like, with the top-cover in the upper position and with the other cover depending downwardly from the hinge-edge of the top-cover and with each of said monthly-calendar panels normally extending downward from said hinge-member but being constructed and arranged to be turned upward and to have its upper edge tucked underneath said flap-portion and to be retained thereby in upwardly-extending position so as to expose the next successive panel and also to expose the major portion of the reverse side of the turned-up panel below said flap-portion; said flap-portion leaving the major back-surface of the

turned-up panel fully exposed when held in place in the turned-up position by said flap-portion.

2. A calendar comprising a top-cover and a plurality of monthly-calendar sheets all pivotally mounted upon a hinge-member whereby the calendar can be closed book-wise and opened and hung on a wall or the like for display in generally vertical position with the top-cover extending upwardly from said hinge-member; said top-cover having an uppermost fold-line and an integrally-formed flap-portion depending therefrom, and a spring-clamp tensioning said flap-portion to closed position, each of said monthly-calendar sheets normally extending downward from said hinge-member but being constructed and arranged to be turned upward and tucked underneath said flap-portion and to be retained thereby in upwardly-extending position so as to expose the next successive sheet, said spring-clamp comprising a strip of thin flat resilient steel or the like transversely folded generally at its center to provide juxtaposed arms normally tensioned to abutting position and constructed and arranged resiliently to grip the flap-portion, at least one of said arms being provided with a pointed locking-ear structure struck out integrally therefrom and bent so as to protrude inwardly with its point extending toward the fold-line so as to prevent dislodgment of said spring-clamp from said flap-portion.

3. A calendar comprising a top-cover and a plurality of monthly-calendar sheets all pivotally mounted upon a hinge-member whereby the calendar can be closed book-wise and opened and hung on a wall or the like for display in generally vertical position with the top-cover extending upwardly from said hinge-member, said top-cover having an uppermost fold-line and an integrally-formed flap-portion depending a short distance therefrom, a spring-clamp fitting over said fold-line and bearing against said flap-portion thereby resiliently to maintain it in closed position, each of said monthly calendar sheets normally extending downward from said hinge-member but being constructed and arranged to be turned upward and to have its upper edge tucked underneath said flap-portion and to be retained thereby in upwardly-extending position so as to expose the next successive sheet and also to expose the major portion of the reverse side of the turned-up sheet below said flap-portion.

4. A calendar comprising a top-cover and a plurality of monthly-calendar sheets all pivotally mounted upon a hinge-member whereby the calendar can be closed book-wise and opened and hung on a wall or the like for display in generally vertical position with the top-cover extending upwardly from said hinge-member, said top-cover having an uppermost fold-line and an integrally-formed flap-portion depending a short distance therefrom, a pair of spring-clamps made of thin flat metal or the like fitting over said fold-line in laterally-spaced relationship and bearing against said flap-portion thereby resiliently to maintain it in closed position, each of said monthly-calendar sheets normally extending downward from said hinge-member but being constructed and arranged to be turned upward and to have its upper edge tucked underneath said flap-portion and to be retained thereby in upwardly-extending position so as to expose the next successive sheet and also to expose the major portion of the reverse side of the turned-up sheet below said flap-portion.

5. A calendar comprising a top-cover and a

plurality of monthly-calendar sheets all pivotally mounted upon a hinge-member whereby the calendar can be closed book-wise and opened and hung on a wall or the like for display in generally vertical position with the top-cover extending upwardly from said hinge-member, said top-cover being integrally formed of cardboard or the like folded into a generally 2-ply structure bent over at its upper edge to provide a depending double-ply flap-portion having a fold-line at its lower edge and having juxtaposed inner and outer fold-lines at its upper edge, and a concealed spring-clamp fitting over the inner fold-line and tensioning said flap-portion to closed position, each of said monthly-calendar sheets normally extending downward from said hinge-member but being constructed and arranged to be turned upward and tucked underneath said flap-portion and to be retained thereby in upwardly-extending position so as to expose the next successive sheet.

6. A calendar comprising a top-cover and a plurality of monthly-calendar sheets all pivotally mounted upon a hinge-member whereby the calendar can be closed book-wise and opened and hung on a wall or the like for display in generally vertical position with the top-cover extending upwardly from said hinge-member, said top-cover being integrally formed of cardboard or the like folded into a generally 2-ply structure bent over at its upper edge to provide a depending double-ply flap-portion having a fold-line at its lower edge and having juxtaposed inner and outer fold-lines at its upper edge, and a concealed spring-clamp fitting over the inner fold-line and tensioning said flap-portion to closed position, each of said monthly-calendar sheets normally extending downward from said hinge-member but being constructed and arranged to be turned upward and tucked underneath said flap-portion and to be retained thereby in upwardly-extending position so as to expose the next successive sheet, said spring-clamp comprising a strip of thin flat resilient steel or the like transversely folded generally at its center to provide juxtaposed arms normally tensioned to abutting position and constructed and arranged resiliently to grip the intervening plies of the flap-portion.

7. A calendar comprising a top-cover and a plurality of monthly-calendar sheets all pivotally mounted upon a hinge-member whereby the calendar can be closed book-wise and opened and hung on a wall or the like for display in generally vertical position with the top-cover extending upwardly from said hinge-member, each of said sheets having the days of the month imprinted on its front side with the days of the week arranged horizontally, and with space provided adjacent each date-imprint for the making of memoranda or the like, the reverse side of each

sheet being imprinted with two smaller-size monthly-calendar representations so that, when a sheet is turned upward its reverse side will show the monthly-calendar representations for the past and coming months simultaneously with the current monthly-calendar representation of the next successive sheet, and means provided at the upper edge of said top-cover for releasably retaining said sheets in turned-up position; said retaining means comprising a depending flap-portion integrally formed at the upper edge of said top-cover and a spring-clamp fitting over said fold-line and bearing against said flap-portion thereby resiliently to maintain it in close position whereby it will frictionally retain the upper edges of turned-up sheets inserted underneath the flap-portion.

8. A calendar comprising a top-cover and a plurality of monthly-calendar sheets all pivotally mounted upon a hinge-member whereby the calendar can be closed book-wise and opened and hung on a wall or the like for display in generally vertical position with the top cover extending upwardly from said hinge-member, each of said sheets having the days of the month imprinted on its front side with the days of the week arranged horizontally, the reverse side of each sheet being imprinted with two smaller-size monthly-calendar representations so that, when a sheet is turned upward its reverse side will show the monthly-calendar representations for the past and coming months simultaneously with the current monthly-calendar representation of the next successive sheet, and means provided at the upper edge of said top-cover for releasably retaining said sheets in turned-up position; said retaining means comprising a depending flap-portion integrally formed at the upper edge of said top-cover and a pair of spring-clamps made of thin flat metal or the like fitting over said fold-line in laterally-spaced relationship and bearing against said flap-portion thereby resiliently to maintain it in closed position whereby it will frictionally retain the upper edges of turned-up sheets inserted underneath the flap-portion.
